UNITED STATES PATENT OFFICE.

CHARLES HAROLD TAYLOR, OF MERE, ENGLAND, ASSIGNOR OF ONE-HALF TO RICHARD WILSON COURTICE, OF BLOEMFONTEIN, ORANGE FREE STATE, SOUTH AFRICA.

GOVERNOR FOR INTERNAL-COMBUSTION ENGINES.

1,133,679.

Specification of Letters Patent.

Patented Mar. 30, 1915.

Application filed August 13, 1914. Serial No. 856,699.

To all whom it may concern:

Be it known that I, CHARLES HAROLD TAYLOR, a subject of the King of Great Britain, residing at Mere, in the county of 5 Wiltshire, in England, have invented certain new and useful Improvements in Governors for Internal-Combustion Engines, of which the following is a specification.

My invention relates to a governing device whereby the amount of fuel supplied to an internal combustion engine is regulated, and particularly to a two-stroke internal combustion engine.

The object of the invention is to provide 15 a governing device which shall regulate the amount of fuel in accordance with the speed so that the latter shall remain constant under varying loads.

A further object of my invention is the 20 provision of a governor which shall be positive in its action on the fuel supply.

Another object of the invention is to provide means whereby a fuel supply, as just noted, may be combined with an air injector 25 for spraying the fuel into the engine.

Other objects of the invention will appear hereinafter the novel combinations of elements being pointed out in the appended claims.

30 Referring to the drawings: Figure 1 represents a longitudinal section of my improved governing device as applied to a two-stroke explosion engine; and Fig. 2 is an end elevation showing the application of 35 the invention to a fuel supply device combined with an air injection apparatus.

Although the governing device is illustrated as adapted to a two-stroke explosion engine it may with slight modifications be 40 used equally as well with engines on the four-stroke cycle.

In the valve gear shown in the drawings, which I have claimed in an application co-pending herewith, filed August 13, 1914, 45 Serial No. 856,698, the lever 12 controlled by the spring 27 operates a fuel plunger 17 through the arm 16, and also an injection air valve 14 through the arm 13, but it must be understood that so far as this invention is concerned the governing occurs 50 in regard to the fuel plunger 17, which is operated on its suction stroke by the spring 18 and closed by the action of the spring 27 on the lever 12, the amount of the delivery stroke of the plunger and conse-

quently of the fuel, being varied by the movement allowed to the roller 26 of the lever 12 where it abuts against the rotary member 10. The rotary member, which in the example illustrated is the cam 10, and is placed directly on the crank shaft 9, is provided with a slanting depression, or flat, 55 of which the highest point is nearly level with the normal perimeter of the cam, and the lowest point descends to the cam boss, 60 which is the position of maximum delivery. The cam 10 also carries a nib 30 projecting above the normal perimeter which, co-operating with the lever 12 and its arm 13, opens the injection air valve 14 against the 65 action of the spring 15, and thus sprays the fuel from the delivery valve 33 through the passage 22, into the combustion space 70 23 where it is ignited by the hot bulb 24. The cam 10 slides on the feather 36, while 75 rotating with the shaft 9, and it is connected to the centrifugal governor 37 whose arms open and close according as the speed of the shaft is high or low, consequently the roller 26 will pass over a different section 80 of the incline 31 for each varying position of the governor arms 37, thereby allowing of the spring 27 increasing the stroke of the fuel plunger 17 when the speed is low, and vice versa when it is high by reason of the 85 roller only slightly entering the depression. Whatever the amount of fuel the injection air will blow it into the cylinder as its force will not vary, being actuated to the same extent at each revolution by the nib 30. The 90 suction stroke of the plunger is actuated by the spring 18, and its extent is limited by a stop 38 so that it is not affected by the cam projection 30 at all. The spring 27 may be attached to any convenient part of 95 the framework and it should be noted that it is really the motive power which works the plunger 17, the cam and its incline being only a controlling device for the travel of the lever 12.

The operations of the two-stroke engine, comprising the main cylinder 1 with its hollow piston 3, extension 4, and the fuel injection apparatus illustrated, are disclosed and claimed in a co-pending application filed by me on August 13, 1914, Serial No. 856,698 for an improvement in two-stroke gas engines.

Having thus fully described my invention and without limiting myself to the precise 110

details of construction or arrangement of parts herein disclosed, what I claim and desire to have protected by Letters Patent of the United States is:—

5 1. The combination with a spring controlled plunger with limited stroke a suction valve and a delivery valve controlling the supply of fuel to an internal combustion engine, of a spring controlled lever member 10 for operating the said plunger, a rotary reciprocating cam mounted on the engine shaft and having a slanting depression on same below its normal perimeter, an arm on the lever member coöperating with the 15 slanting depression on the cam to regulate the delivery stroke of the fuel plunger, a centrifugal governor boss adjoining the said cam attached to and rotating about the same shaft in unison with the cam, weighted an- 20 gular levers pivoted on the said governor boss and connected directly to slots in the cam boss, and a spring encircling the engine shaft interposed between the cam boss and the governor boss, substantially as and for 25 the purpose set forth.

2. The combination with a spring-controlled fuel admission device and spring-controlled air injecting device on an internal combustion engine, of a spring-con- 30 trolled lever member for operating the said devices, a rotary reciprocating member controlling oscillation of the lever member and having its rotation in fixed ratio to the speed of the engine, a projection at one place on 35 the rotary member, a surface at a second place on same which slants relatively to the direction of reciprocation, an arm on the lever member controlling the fuel admission device through the medium of the slanting 40 surface on the rotary member, an arm on the lever member operating the air injection device through the medium of the projection on the rotary member, and means for vary- 45 ing the reciprocatory position of the rotary member in accordance with the speed of the engine.

3. The combination with a spring-con- 50 trolled fuel admission device and a spring-controlled air injecting device on an internal combustion engine, of a spring-con- 55 trolled lever member for operating the said devices, a rotary member controlling oscil- lation of the lever member, a sliding con- nection between the rotary member and its supporting shaft, a projection at one place on the rotary member, a surface at a second place on same which slants relatively to the

direction of reciprocation, an arm on the lever member controlling the fuel admission device through the medium of the slanting 60 surface on the rotary member, an arm on the lever member operating the air injecting device through the medium of the projection on the rotary member, and a centrifugal governor connected to and rotating in uni- 65 son with the rotary member so that the longitudinal position of the latter on its support is dependent upon the speed of rotation, substantially as described herein.

4. The combination with a spring-con- 70 trolled fuel admission device and spring- controlled air injecting device on an internal combustion engine, of a spring-controlled lever member for operating the said devices, a cam on the engine shaft having a sliding 75 connection thereto, a projection at one place on the cam above its normal perimeter, a slanting depression on the same below its normal perimeter, an arm on the lever mem- 80 ber coöperating with the slanting depres- sion on the cam to regulate the fuel admis- sion device, an arm on the lever member co- 85 operating with the projection on the cam to regulate the air admission device, and a centrifugal governor carried by the engine 90 shaft in connection with the sliding cam thereon.

5. The combination with a spring-con- 90 trolled plunger of limited suction stroke a suction valve and a delivery valve control- 95 ling the supply of fuel, and a spring closed valve controlling the supply of injection air to an internal combustion engine, of a spring controlled lever member for operat- 100 ing the said plunger and the said air valve, a cam on the engine shaft having a sliding connection thereto, a projection at one place on the cam above its normal perimeter, a slanting depression on the same below its normal perimeter, an arm on the lever mem- 105 ber coöperating with the slanting depression on the cam to regulate the delivery stroke of the fuel plunger, an arm on the lever member coöperating with the projection on the cam to regulate the air admission valve, and a centrifugal governor carried by the engine shaft in connection with the sliding cam thereon.

In testimony whereof I have affixed my signature in presence of two witnesses.

CHARLES HAROLD TAYLOR.
